HIGHWAY GUARDRAIL CONSTRUCTION

Eugene V. Camp, Atlanta, Ga.

Application September 16, 1936, Serial No. 101,069

15 Claims. (Cl. 256—13.1)

This invention relates to guardrails, and more particularly, to an anchoring and/or reinforcing structure intended primarily for use with road guards of the plate type.

It is well recognized among highway engineers that a traffic guard can be no stronger than its supports and anchoring means, and for this reason it is particularly important that the posts or other members used to uphold and maintain the impact and cushioning elements of the rail in operative position, be themselves held and maintained in proper and positive alignment at all times, and anchorage be provided at certain locations in such a manner as to resist maximum shocks under impact.

An object of my invention is to provide an anchoring means for guardrails, which is simple in structure and thoroughly effective for the intended purposes.

Another object is to provide such a device that is easily installed, either initially, or as an improvement on guards already in position.

Another object is to provide facility of adjustment of such an anchoring means once it is in place.

Another object is to provide a high degree of adaptability in a device of the instant class.

A still further object is to provide cheapness of construction in guardrail reinforcing means.

Another object is to provide still further anchoring means for the primary cushioning elements of road guards of the modern type, which means are simple in structure, economical to manufacture, easy to install, and thoroughly effective for their intended purposes.

Summarized, the objects of my invention are to provide an anchoring and reinforcing structure for road guards, which will serve to produce a more effective and more satisfactory composite structure, better fulfilling the ultimate aim and purpose of certain of my inventions in this field, which purpose has as its inception the guarding and making safe of public highways.

In order that my invention may be fully understood, reference is made to the drawings accompanying and forming a part of this application, in which:

Fig. 1 is a front elevational view, partly fragmentary, illustrating a section of guardrail embodying part of the instant invention.

Fig. 2 is a top plan view of the structure illustrated in Fig. 1.

Fig. 3 is an enlarged front view of the primary anchoring member of the instant invention.

Fig. 4 is a top view of the structure illustrated in Fig. 3.

Fig. 5 is a fragmentary view of the structure shown in Figs. 3 and 4, illustrating a modification of the device thereof.

Fig. 6 is a front elevational view of an additional element which may form part of the anchoring structure contemplated by my invention.

Fig. 7 is a side view of the structure illustrated in Fig. 6, showing in greater detail the foregoing modification.

Like numerals refer to corresponding parts throughout the various figures of the drawings.

Referring now to the drawings (Figs. 1 and 3), in which my invention is illustrated in conjunction with a resilient plate type of road guard such as described and claimed in my basic Patent No. 1,793,673, and Patent No. 1,793,676, both issued February 24, 1931; said road guard in a preferred form comprising supports 10, spring cushioning or buffer elements 11, and resilient impact members 12 interlaced at their ends and secured to opposite sides of elements 11 by bolts 13 in such a manner as to provide a continuous road guard; it will be apparent that my present invention comprises in part, generally C-shaped 15 stirrup-like anchoring members 14, which elements are more particularly described as follows:

Elements 14 may be formed of strip steel or other suitable material, and may be either rigid or slightly resilient as desired. The upper and lower ends 15 and 16 of 14 are formed to lie parallel in substantially the same vertical plane, and said ends may be drilled as at 17 and 18 to receive bolt 13; which bolts are substantially the same as the elements normally used to attach the impact members to the buffer elements in the aforementioned road guard, with the exception that said bolts are preferably provided with nuts 13a, in order to insure a permanent attachment of element 14 to the guard proper, which attachment will not be disrupted by impacts to the guard, or by other causes.

Intermediate of ends 15 and 16, element 14 may be provided with a flattened surface 19 having an aperture 20 to permit the passage therethrough of an anchoring rod 21, which rod is threaded and provided at its upper end with a washer 22 and nut 23, said elements by bearing on surface 19, permitting adjustment of the anchoring rod per se and of stirrup 14. At its opposite end, rod 21 engages an anchoring element or "dead-man" 24, as by being passed through such and held in engagement therewith by nut 25, element 24 being of any desired size

or shape, but preferably of a structure presenting a maximum surface to oppose its being uprooted once buried in the ground, the shape illustrated in the drawings (Figs. 3 and 4) having 5 been found desirable for this purpose.

A modification of the means whereby rod 21 is associated with stirrup 14, is shown in Fig. 5, in which a suitable coil spring 26 is interposed between washer 22 and surface 19, nut 23 serving 10 to hold the assembly in place. In this manner the tension under which rod 21 joins 14 may be varied, and at the same time a further spring element provided to cushion and soften the force of impacts to the guard rail, the posts thereof, 15 and the anchoring means described herein, and also to aid in compensating conditions caused by atmospheric temperature changes.

Since it appears that the above-described structures may be responsible for a somewhat 20 greater vertical displacement to buffers 11 under impact, than in the case of conventional road guards now in use, it may be desirable to further reinforce said elements 11 against displacement, in the manner shown in Figs. 6 and 7 of the 25 drawings, which figures illustrate members 11a joined to supports 10 as by bolt 27, washer 28 and nut 29, bolt 27 being first passed through reinforcing or check-plate 30, to which special attention is now directed.

30 Plate 30 is formed of steel or other suitable material, preferably of somewhat greater thickness than the element 11a, and through its upper portion has an aperture 31 to receive bolt 27 as previously indicated. The lower portion of 30 35 is turned more or less at right angles to form a check element 32, which is intended to engage a slot or groove 33 provided in post or support 10 for such purpose. Thus it is apparent that when the elements are in place and nut 28 tightened 40 on bolt 27, 11a is definitely anchored against turning or sliding on post 10 either under impact or from stresses set up in anchor rod 21 by adjustment, changes in temperature, or otherwise.

From the foregoing description the operation 45 of my invention will be apparent to those skilled in the art, it being clear that stirrups or reinforcing members 14 when associated with buffers 11 in the manner described herein, at proper intervals, produce a guardrail structure having greater stability, a greater resistance to shocks and strains, and more permanence than has heretofore been possible. Members 14 with described anchorage means serve to anchor the guardrail structure in such a manner as to resist 50 severe strains, and when made more or less resilient, or when associated with a supplemental spring element as shown in Fig. 5 of the drawings, said device affords greater springiness to the guardrail structure as a whole, thereby further cushioning the effect of shocks and impacts thereto, and reducing the damage to both vehicle and guard therefrom.

When members 11a are provided with the stabilizing element 30 illustrated in Figs. 6 and 7, 55 an additional reinforcement results to the guard, the elements thereof being further held in contemplated position and adjustment so as to function at all times in the optimum manner, where previously described anchors are used.

70 While I have illustrated herein a preferred embodiment of my invention, it is not my intention to be limited by or to such disclosure. For instance, the present device may be used in other road guards from that illustrated herein, my 75 reinforcing elements being peculiarly adapted for

use with cable guards employing cushioning and connecting members after the manner taught broadly by my Patent No. 1,793,674. It is my further intention that the appended claims shall be liberally construed in keeping with my present contribution to the art. 5

I claim:

1. A guardrail comprising a series of posts, a series of buffer members attached to said posts, and an impact member extending from buffer 10 member to buffer member and being supported thereby, stirrup-like anchoring members pivotally mounted to opposite sides of one of said buffer members, an anchoring rod joined to each of said anchoring elements, and means for holding said 15 rods firmly in the ground.

2. A guardrail comprising a series of posts, a series of buffer members attached to said posts, and an impact member extending from buffer 20 member to buffer member and being supported thereby, a stirrup-like anchoring element pivotally mounted to one of said buffer members, an anchoring rod joined to said anchoring element, and anchoring means for said rod.

3. A guardrail comprising a series of supports, 25 a series of buffer members attached to said posts, an impact member extending from buffer member to buffer member and being supported thereby; stirrup-like anchoring elements at intervals pivotally mounted to opposite sides of said buffer 30 members, an anchoring rod adjustably mounted to each of said anchoring elements, and means for holding said rods fixedly in the ground.

4. A guardrail comprising a series of supports, 35 a series of buffer members attached to said supports, an impact members extending from buffer member to buffer member and being supported thereby; a stirrup-like anchoring element pivotally mounted to one of said buffer members, an anchoring rod penetrating said anchoring 40 element, a spring on said rod between said point of penetration and the end thereof, and means for holding said rod fixedly in the ground.

5. A guardrail comprising a series of supports, 45 a series of buffer members attached thereto, an impact member extending from buffer member to buffer member and being supported thereby; an L-shaped plate engaging the rear of one of said buffer members on the inside thereof, a horizontal groove in the support adjacent said 50 buffer member, said L-shaped element extending into said groove in such a manner as to prevent displacing of the buffer member on the support; a stirrup-like anchoring element mounted to said buffer member, an anchoring rod associated with said anchoring element, and means for anchoring said rod fixedly in the ground. 55

6. A guardrail comprising a series of supports, 60 a series of buffer members attached thereto, an impact member extending from buffer member to buffer member and being supported thereby; an L-shaped plate engaging the rear portion of one of said buffer members, and a horizontal groove in the support adjacent said buffer member, said L-shaped element extending into said 65 groove in such a manner as to give added stability to the buffer member on the support.

7. In a guardrail construction, an impact member, spring cushioning elements associated therewith, supports for said impact member and 70 springs, stirrup-like anchoring members pivotally mounted to said springs, anchoring rods engaging said anchoring members, and an anchorage at one end of each of said anchoring rods.

8. A guardrail comprising a series of supports, 75

- 5 a series of buffer members attached thereto, an impact member extending from buffer member to buffer member and being supported thereby; a check plate engaging the rear portion of one of said buffer members, and stop means for said plate in the support adjacent said buffer member, said plate engaging said stop means in such a manner as to afford added stability to the buffer member on the support.
- 10 9. A guardrail comprising a series of supports, a series of buffer members attached thereto, an impact member extending from buffer member to buffer member and being supported thereby; a check plate engaging the rear portion of one of said buffer members, and anchoring means for said plate associated with the support adjacent said buffer member, said plate engaging said anchoring means in such a manner as to afford added stability to the buffer member on the support.
- 15 10. A guardrail comprising a series of supports, a series of buffer members attached thereto, an impact member extending from buffer member to buffer member and being supported thereby; and a check plate engaging the inner portion of one of said buffer members and extending to the adjacent support in such a manner as to provide added stability to the buffer member on the support.
- 20 11. A guardrail comprising a series of supports, impact members extending along said supports, one impact member interlaced through an adjacent impact member and their contiguous ends attached to resilient anchorage means.
12. A guardrail comprising a series of supports, a series of buffer elements attached thereto, impact members extending from buffer element to buffer element, one impact member interlaced through an adjacent impact member and their contiguous ends being attached to fixed anchorage means.
13. A guardrail comprising a series of supports, impact members extending along said supports, one impact member interlaced through an adjacent impact member and their contiguous ends connected to resilient anchorage means.
14. A guardrail comprising a series of supports, impact members supported by said supports, one impact member interlaced through another and the ends of such interlaced impact members being attached to fixed anchorage means.
15. A guardrail comprising a series of supports, impact members extending along said supports, one impact member interlaced through an adjacent impact member and their contiguous ends attached to anchorage means.

EUGENE V. CAMP.
